BUILDING CONSTRUCTION

Harold S. Curren, Rochester, N. Y., assignor, by
mesne assignments, to Curren Fabrihome Cor-
poration, Willoughby, Ohio, a corporation of
Delaware

Application October 28, 1936, Serial No. 107,931

15 Claims. (Cl. 20—4)

This invention relates to a building construction and the general object is to provide a method and arrangement by which essential building elements, partitions and other parts may be erected economically and quickly without requiring the exercise of any considerable skill or craftsmanship on part of the workmen.

Further objects include the provision of a new unit partition structure, and a new method and arrangement for insulating dwelling houses and other buildings against ingress of weather elements, heat loss, etc.

A more comprehensive object is to provide a sectional wall which, when in place, will be one homogeneous whole, securely locked in position, which will rest on or be suspended on a cushion which will take up any contraction or expansion of the materials from which the wall may be made, thus eliminating cracks and disfigurements of surface treatments, such as plaster, stucco, paint and wallpaper, and eliminating transference of any strain or stress (caused by distortion or deflection of the skeleton structure) to the wall panels, and conversely to eliminate any stresses and strains, caused by the contraction or expansion of the wall panels, from being transferred to the skeleton structure.

Other objects and features of the invention will become apparent from the following description relating to the accompanying drawing, which shows a preferred embodiment and the preferred procedure in carrying out the method.

In the drawing, Fig. 1 is a sectional view, showing portions of two floor slabs and a wall unit in place therebetween; Fig. 2 is a relatively enlarged vertical sectional view, through such wall or partition unit and its upper and lower supports; Fig. 3 is a fragmentary sectional broad-face view of portions of two wall or partition units; Fig. 4 is a relatively enlarged detail sectional view, taken on the line 4—4 of Fig. 3, of a yielding wall-supporting device; Fig. 5 is a perspective view of a spring wedge; Fig. 6 is a broad-face view of a wall or partition with a door frame therein; Fig. 7 is a horizontal sectional view taken on a line corresponding to the line 7—7 on Fig. 3, but showing the right hand end of the assemblage which is broken away in Fig. 3, and Figs. 8 and 9 are detail sectional views, as indicated by the lines 8—8 and 9—9 respectively on Fig. 6.

Referring to Figs. 1 and 2, these show concrete floor slabs 1 and 2 supported on an outer concrete skeleton structure 3 which may be of any nature. Lower and upper retaining seats 22 and 32 for the wall unit sections are suitably formed,

as in the concrete, the seats comprising channels each having effective "floor" portions 5 which slope gradually outwardly from abrupt walls 6 which are to abut and definitely locate the wall sections or panels as will be described below. The 5 building parts and channels referred to in this paragraph may be made of any suitable constructional materials,—wood, metal, concrete, etc. In the event the channels or seats are formed in concrete, wire beads 7 (Fig. 2) preferably reinforce the upper corner portions of the channel; such beads being held during and after setting of the concrete by leg members 15 which may be rigid with the beads. The manner of erecting a suitable skeleton structure including the seats 15 or channels will form the subject matter of a separate application (divided from this case).

The drawing illustrates a procedure using concrete for the floor structure and other portions of the building, but, the invention is in no way confined to such construction. Fixed channels 22 and 32 may be formed in such concrete as shown in Figs. 1 and 2, these having gradually sloping bottom surfaces 5 (bottom inverted in upper channel) and abrupt walls 6, preferably at one 25 side only of each channel.

The wall or partition units or sections P may be made of any convenient width (say four feet) and of a height which is sufficiently less than the distance from the bottoms of the channels 22 to 30 the tops of the channels 32 to allow for their insertion into said channels. The upper and lower ends of the sections may be sloped or beveled substantially complementary to the respective sloping surfaces of the channels. If the lower channels are 1 1/4 inches maximum depth and the upper channels 5/8 inch, the wall units may easily be inserted if made 1 inch longer than the distance between floor and ceiling.

The units or sections are hollow, for lightness 40 in weight, for insulation, and to provide adequate space for any ducts for heating, lighting, sanitation, ventilation, etc., that may be desired.

In Figs. 2 and 3, four studs 40 and 41 are shown as connected together by cross-pieces 42 45 inset into the edge faces of the studs, and also by inclined top and bottom closure pieces 43 and 44 (fastening not shown). The inclination of the top and bottom edges is substantially the same as the slope of the respective channels 22 and 32. 50 The pieces 43 and 44 may be set into indentations in the adjacent cross-pieces and the studs, as shown or suggested in Fig. 2.

The unit framework may be faced on one or both sides by panels which comprise preferably 55

(in case of an outer wall section) laminated paneling 45 on the outside and wall board, such as plaster board or fiber board 45a on the inside. In case the paneling 45 is plywood this preferably has moistureproof adhesive between the layers. In case of an inner wall or partition, the same facing would usually be used on both sides, say plasterboard or plaster lath. Hand holes 40a may be made in the edge studs 40 to facilitate erection. These are offset vertically on opposite edges of the units, so they will not align on edge-wise adjacent units.

Attention is called to Fig. 4 in which it is seen that the facing (45, 45a) projects a short distance 15 beyond the studs 40 at the vertical edges of the units. This provides spaces for spline strips 47, between adjacent sections, which splines are attached to the studs 40 by a suitable adhesive; preferably a high water-resistant glue, such as 20 casein or soybean base glues.

An insulation lining is shown in Fig. 2, comprising a filler of rock-wool 48 (or equivalent insulation mass or "fill"), held in place by sheets 49, substantially of moisture-impervious material, such as kraft paper impregnated with asphalt or the like. Such sheets may be marginally stapled as indicated at 49a, to the framework of the unit; the framework, preferably including a horizontal cross-strip 46. This leaves 30 plenty of room for ducts, plumbing, etc.

The units or sections P are set into the lower channels, as indicated in broken lines in Fig. 1, and then swung up into place as shown in full lines. When one end of a section (or group of 35 sections) is temporarily seated in one channel (as suggested in Fig. 1), the beveled opposite end can then be swung across the sloping surface 5 of the opposite channel against but not past the abrupt wall 6 thereof. Thus, e. g. the sections or units 40 are retained against falling inwardly until secured, for example, as described below, and when so secured the sections cannot move either inwardly or outwardly.

After erection of the sections, as above described, wedges 50 (see Fig. 5), preferably made as bent strips of sheet metal are driven in at one horizontal edge of each section, as below the studs 40 and 41, far enough to shift the sections into seated position in the opposite channel. 45 Preferably, the upper edges of the units are sealed by applying thereto strips of material, such as 50 impregnated felt or roofing paper 52, the margins of which may project beyond the portions of the units which are embraced by the upper channels, 55 as shown in Fig. 2.

When a complete line of sections has been erected with intervening, splines, as above described, these are bound into one integral unit by tie wires 55 which may be guided, for insertion, 60 by tubes 56, say of paper or metal inset into aligned bores in the studs. Since the tie wires are free to shift lengthwise across the joints between adjacent sections, tightening of all the joints may be effected at one edge of an assembled unit comprising any desired number of sections. The wires may be headed at one lateral edge of the partition structure and tightened as by a yoke-type clamp at the other edge. A suitable tightening device is illustrated in Fig. 7 comprising a yoke 57 carrying a threaded draw-bolt 58, the inner end of which is adapted to engage a loop 55a of the tie wire 55 and draw it tight. Such tightening devices may readily be operated by a socket wrench engaging nuts 59 on the draw 75 bolts.

After the sections P are clamped together, as described, forming rigid units, the ends of the wires may be electrically welded to retaining washers 60, Fig. 7; the projecting loops 55a then cut off, and the yokes 57 removed. Where columns occur at both ends of the composite partition or wall units, the last section is pulled tight while one or more sections is or are in outwardly swung position, and the tie wires secured at the far edge of the last section before it and adjacent 10 sections are fully seated into the channels.

After clamping of the composite unit as above described, and seating all sections in the channels 22 and 32, the spring wedges 50 are then driven in as far as they will go and the gap below the unit 15 is filled in by caulking compound or the like to keep out moisture. Springs of various weights and designs may be used, according to the load to be carried. The wedge springs may be reinforced by rubber blocks 61, Fig. 2, if desired. 20 Each entire line of partition sections is now one rigid composite unit, sealed and inset above and below with relation to the channels 22 and 32, and yieldingly supported on the springs. Sealing and joining of the vertical edges of the composite 25 units may be accomplished by caulking or in any other suitable manner.

While not claimed herein, it is deemed advisable to show how the necessary door or window openings may be finished,—(novel features to be 30 claimed in a separate case). Such door or window passages through the walls and partitions provided as above described, may be finished as shown in Figs. 6, 8 and 9. In Fig. 6, P' is a short 35 partition unit made up by cutting a regular length section and inserting a stud section horizontally near the lower edge as at 65 leaving the facings 45 and 45a projecting beyond it as shown in Fig. 9. The facings project beyond the studs 40, as already described. Lintels 70 and Jamb 40 members 71 are movably mounted between the projecting facings, as by screws 73 and 74, which enter the members 65 and 40 respectively. The screws do not hold the lintel and jambs tight against the partition unit framework, but instead 45 compress stiff leaf springs 75 theretoward (see Fig. 6), which springs lie in appropriate sockets 76 in the lintel and jambs 70 and 71, as shown in Fig. 8 and 9.

The door trim may comprise special spring 50 metal channel shapes 78 and 79, made to fit the jambs and lintels and yieldingly to embrace the facings as at 80 (snapped over). The upper trim member is coped to slide into place between and fit the trim members 79, the side trim being moved 55 outwardly sufficiently to clear the coped top trim and avoid scratching the finish on the side trim. This is done by means of the screws 74. Afterward the screws 74 may be unscrewed allowing the spring 75 to force the side members 79 inwardly whatever amount is necessary to fit the doors. Thus, the doors and windows are made to fit their openings exactly or with a great or as little clearance as desired without having to go 60 through the tedious procedure of making extremely accurate measurements and without having to cut and try.

I claim:

1. A building wall, made of edgewise aligned 70 sections operatively interlocked at their top and bottom edges with upper and lower fixed seats and resting on springs associated with the lower seats, said springs being insertable beneath the sections after the same are erected and render- 75

ing the upper seats effective to retain the sections.

5. A building wall, made of edgewise aligned and interlockingly abutting sections sealed at their top and bottom edges in upper and lower fixed seats, the sealing means including plastic material on one of the seats and springs associated with such seat, embedded in the plastic sealing means and forcing the sections toward the 10 other seat.

6. A building wall comprising longitudinally aligned and operatively interlocking sections forming a composite wall unit, fixed means adapted to retain the upper edge of such unit, 15 fixed means including a channel for initially receiving the lower edge portion of the unit, and spring wedges which lift said lower edge portion away from the floor of the channel and which support the unit in interlocking engagement with 20 the upper retaining means rendering the latter effective to hold the upper portion of the unit in position during the use of the building.

7. In building construction, a wall made up of edgewise adjacent sections adapted to occupy 25 upper and lower recesses in spaced fixed building parts, each section having a bevelled surface at one end, the recess for engaging such end being substantially complementarily bevelled, and means cooperating with the opposite end and the 30 adjacent recess to shift the section in its own plane in a manner to force the bevelled end tightly into engagement with the complementary recess.

8. In building construction, pre-fabricated unit 35 sections having bevelled edges at their tops and bottoms, means forming upper and lower channels with sloping top and bottom surfaces spaced wider than the length of the sections and adapted to receive the sections when the same are seated 40 in a lower channel and tilted toward the upper channel, and wedging means adapted to be driven between the sections and one of said channel surfaces to retain the sections in place.

9. A sectional building construction, wherein 45 edgewise aligned upright wall or partition sections are interlocked with each other and clamped together, the upper and lower edges of which sections are bevelled in opposite directions, and means including similarly bevelled channels 50 in the upper and lower fixed building structures operatively receiving and retaining the bevelled ends of the sections.

10. A composite building wall unit comprising a plurality of sections which operatively interlock with each other edgewise, said sections being adapted to be erected into retaining means 55 above and below them, and elongated means passing through a plurality of such sections, forcibly tying the sections together, said elongated 60 means being shiftable bodily lengthwise of itself across the regions of interlock between the sections so that said means can be operatively headed at two edges of the assembled unit to secure any desired number of sections comprising 65 the unit.

11. A composite building wall unit, comprising a plurality of edgewise adjacent hollow frame sections adapted to be erected in wall or partition form, tie-wires passing through guides in 70 the hollow framework of the sections from one section to another and shiftable freely across the joints between sections after assembly thereof, and means for retaining the tie-wires.

12. A composite building wall unit, made up of 75 edgewise aligned sections, each having a core

frame and a facing, the margins of which facing extend beyond the core frames, splines seated between said sections, and clamping means extending from section to section through the splines and shiftable freely transversely thereof after the splines and sections are assembled, to hold the aforesaid elements of the units rigidly together. 5

13. In sectional building construction, a plurality of hollow building sections, having studs, 10 facing covering the studs, means to secure one edge of such section on one supporting building wall structure, and spring wedges adjacent an opposite supporting wall structure and located in vertical alignment with the studs for operative 15 engagement with the sections in the individual vertical planes of such studs, for securing the section to such opposite supporting wall structure and maintaining the section forced against the first named securing means. 20

14. In sectional building construction, a plurality of hollow building sections, each having a hollow framework and facings covering the framework, means to secure opposite edges of the sections on upper and lower fixed supporting 25 members, insulation means within the framework adjacent one facing, and retaining webs of moisture impervious material retaining the insulation means in place and dividing the section to form a duct reception space inwardly from the 30 other facing.

15. The method of constructing building elements comprising erecting wall sections by temporarily locating the edges in recesses of spaced parts of the building, then clamping the sections 35 together into edgewise relationship, and finally driving spring wedges beneath the sections so as to hold them in firm contact with the recesses.

16. A building wall comprising longitudinally aligned and operatively interlocking sections 40 forming a composite wall unit, fixed means adapted to retain one horizontal edge of such section against movement normal to its principal plane inwardly and outwardly, fixed means including a channel adapted for initially receiving 45 and locating the opposite horizontal edge of the section, and wedge means adapted to be driven between the latter horizontal edge and the effective floor portion of the channel to cause the section to be shifted relative to the first 50 named fixed means in a manner to render the same effective to retain the section as stated.

17. In a building construction wherein wall sections are operatively seated in fixed retainers spaced wider apart than the sections are long, the 55 combination wherein one retainer comprises a channel having a gradually sloping surface and, adjacent thereto, an abrupt wall; and the end of such section which operatively seats in the channel is beveled substantially complementary to the 60 sloping surface; said section when placed with an end seated in the retainer opposite the channel being capable of having its beveled end swung across the sloping surface and against the abrupt wall, but not past it. 65

18. The method of constructing building elements comprising erecting wall sections by temporarily locating the edges in recesses of spaced parts of the building, then clamping the sections together into edgewise relationship, and finally 70 driving wedges between one horizontal edge of each section and an adjacent building recess to hold the section in firm contact with the opposite recess.
